UNITED STATES PATENT OFFICE.

LESTER CLARK WHITAKER, OF SANTA ROSA, CALIFORNIA.

TIME-SWITCH FOR ELECTRIC CIRCUITS.

Specification of Letters Patent.

Patented Aug. 19, 1919.

1,313,440.

Application filed March 1, 1918. Serial No. 219,887.

To all whom it may concern:

Be it known that I, LESTER C. WHITAKER, a citizen of the United States, and a resident of Santa Rosa, in the county of Sonoma and State of California, have invented a certain new and useful Improvement in Time-Switches for Electric Circuits, of which the following is a specification.

My present invention relates to electric circuit control devices, and more particularly to a switch mechanism to be associated with a clock or other suitable operating parts to be actuated to open and close the circuit at predetermined times.

The principal object of my invention is to provide a switch of the character described, the parts of which may be fitted to and secured in conjunction with an alarm clock or other time piece of ordinary construction, and with which the circuit will be completed and broken at predetermined times during operation of the clock mechanism.

Other objects of my invention are to provide switch mechanism of the character described which is simple in construction, compact, neat in appearance, and which may be arranged in existing circuits and embodied with an ordinary clock mechanism, or mechanism of a similar character, to provide a unitary time circuit control device, the parts at the same time being so constructed that when the circuit connection is broken there will not be tendency to arc between the circuit terminals.

Further objects of my invention will appear in the following detailed description, taken in connection with the accompanying drawing, forming a part of this specification, and in which drawing:

Figure 1 is a view in elevation showing the structure of my invention as the same is fitted to an alarm clock and diagrammatically illustrating a circuit connection.

Fig. 2 is a fragmentary top plan view of the structure disclosed in Fig. 1 to better illustrate the construction and fitting of the switch parts.

In the drawing, where similar characters refer to similar parts in each of the views, the clock mechanism, which might be an ordinary alarm clock, is designated at A, and this time mechanism has a commutator structure B mounted on the hand spindle or shaft. Circuit wires C and D lead from the

main line wires E and F to the brushes G

and H, the lamps I being connected in the branch circuit wires.

As has been stated, the time mechanism or clock A is of substantially standard form, and the commutator structure B which includes a disk 1 of fiber or other suitable insulating material having a segmental plate 2 of brass or suitable conducting material carried thereby, has a sleeve 3 carried centrally on the inner side thereof to be received over the hand spindle or shaft of the clock, a set screw 4 being provided to fix the commutator structure on this spindle or shaft in the proper mounting. A bracket 5 is mounted on the clock casing and an insulating block 6 is carried thereby, the brushes G and H being mounted on this insulating block, and binding screws 7 and 8 being provided for attachment of the circuit wires C and D in connection with these brushes G and H.

It will of course be appreciated that the brushes G and H will be separated a sufficient distance that an arc will not be set up therebetween at any time, and to properly guide the contact terminals of these brushes and to insure that they will not at any time be brought closer than the predetermined distance, the commutator structure has guide grooves 9 and 10 formed peripherally there-around and extending through both the insulating and the conductive material. It will of course be appreciated that the segmental conductive member 2 might be made of greater or lesser length than is shown, the length of this member of course depending upon the period of time during which the circuit connection is to be maintained, and that proper setting of the commutator portion C may be made, a hand 11 is provided.

The operation of the time switch is as follows:

Assuming that the parts are set up and connected in a circuit as shown in the drawing, and that the segmental member 2 is made of such length that it extends around substantially one third of the circumference of the commutator portion, which will mean that the segmental member occupies a space corresponding substantially to four hours as indicated on the clock dial, the commutator portion will be set at such a point that when the hand 11 indicates on the clock dial the time at which it is desired that the circuit be closed, the segmental member 2 will at its forward edge bridge across between

105

110

the brushes G and H, and then the setting mechanism of the clock is operated to swing the hand 11 to a position to correspond with the standard time. As the clock mechanism 5 operates, the hand 11, which corresponds to the hour hand of a clock, will be moved around the clock dial, and when this hand arrives at an indicating position designating the time at which the circuit is to be 10 closed, the member 2 will bridge between the brushes and the circuit will be closed, this circuit connection being maintained until the commutator member or portion B has traveled a distance sufficient that the segmental member 2 has passed from beneath 15 the brushes G and H. As the brushes are guided in the grooves 9 and 10, there will be no lateral shifting or bending of the same and in consequence all danger of arcs when 20 the parts are in the circuit opening position will be avoided. It is understood that if the voltage current is such as to cause destructive arcs between the brushes G and H and the member 2, an ordinary condenser may be 25 interposed in this circuit.

While I have herein described the time switch mechanism as connected in and to control a lamp circuit, it will be appreciated that this is only one use of the device and 30 that it might be employed in a number of different connections. Other changes in details may be made without departing from the spirit or scope of my invention; but,

I claim:

35 1. A time switch for electric circuits including with a clock mechanism, a commutator structure consisting of a disk of insulating material having a segmental conductive member carried thereby and which disk 40 is provided with a sleeve adapted to be fitted adjustably upon the hand spindle or shaft of the clock, a set screw by which the commutator structure is fixed upon the spindle or shaft, a hand to guide in setting the

commutator structure, a bracket carried by 45 the clock casing and having an insulating block supported thereby, said commutator structure having guide grooves formed peripherally thereon and spaced, brushes carried by the insulating block and having their 50 ends received in the grooves of the said commutator structure, and binding screws by which the terminals of the circuit to be controlled are connected with said brushes.

2. In a time switch for electric circuits including with a clock mechanism, a commutator structure comprising a disk of insulating material having a segmental conductive member carried thereby, a sleeve carried by 55 said disk and adapted to be adjustably fitted upon the hand spindle or shaft of a clock, a set screw carried by said sleeve for engagement with the spindle to fix the commutator structure upon the spindle or shaft, said commutator structure having guide grooves 60 in its periphery, brushes carried by the clock structure and having their ends received in the grooves of said commutator structure, and binding screws by which the terminals of the circuit may be controlled, connected 65 to said brushes.

3. In a time switch for electric circuits, the combination of a clock mechanism including a hand spindle, and a casing, a commutator structure comprising a disk of insulating material, a segmental conducting member carried by said insulating material, means for adjustably connecting said disk 75 to said hand spindle, a bracket carried by the clock casing, an insulating block carried 80 by said bracket, brushes carried by said insulating block and having their edges riding upon the periphery of said commutator, means for maintaining said brushes in spaced relation, and binding screws by 85 which the terminals of the circuit to be controlled may be connected with said brushes.

LESTER CLARK WHITAKER.
